RALPH E. OGDEN, OF LAWRENCE, NEW YORK, ASSIGNOR, BY MESNE ASSIGNMENTS, TO J. EDWARD OGDEN COMPANY, OF NEW YORK, N. Y., A CORPORATION OF NEW JERSEY

EXPANSION SHIELD

Application filed August 27, 1927. Serial No. 215,783.

This invention relates to improvements in expansion shields of the character employed for obtaining anchorage in walls of brick, stone and cementitious material not adapted 5 to directly receive a threaded member.

One of the objects of the invention is to provide an expansion shield so constructed and arranged as to possess superior gripping qualities.

10 Another object of the invention is to provide an expansion shield adapted to be used with and expanded by a driven expanding member.

Another object of the invention is to provide a "drive in" expansion shield of relatively hard metal having a sleeve of relatively soft or ductile metal disposed on the outer surface thereof and so constructed and arranged that the soft metal sleeve will be expanded laterally when the expanding member 20 is driven into the shield but will not be forced longitudinally of the shield.

Another object of the invention is to provide an expansion shield of the character 25 specified that is economical to manufacture, comprises a minimum number of parts and is practical and efficient in operation.

Further objects of the invention will appear from the following specification taken in 30 connection with the drawings, which form a part of this application, and in which

Fig. 1 is a sectional elevation of a shield constructed in accordance with the invention;

Fig. 2 is an elevational view of the shield 35 shown in Fig. 1;

Fig. 3 is an end view of the shield shown in Fig. 1;

Fig. 4 is a sectional view taken on line 4—4 40 of Fig. 2;

Fig. 5 is an end view of the shield shown in Fig. 1; and

Fig. 6 is a longitudinal sectional elevation 45 showing the shield of Fig. 1 mounted in the wall opening and illustrating an expanding element and an object retained between the shield flange and the wall of the structure in which the shield is mounted.

The invention briefly described consists of 50 an expansion shield comprising an elongated tubular member formed of a pair of sections.

The sections are tapered longitudinally to form a bore tapered from end to end and smaller at the inner end than at the outer end thereof. Each section has a flange projecting laterally from each end thereof, the flanges being disposed in alinement when the sections are secured to form the tubular member. The shield sections are preferably formed of relatively hard sheet metal and a sleeve of relatively soft or ductile metal is 60 mounted on the outer surface of the tubular member formed by the sections and is disposed in abutting relation to the inner flanges. The sleeve of ductile metal is tapered in thickness from end to end and is thicker at its inner 65 end than at the other end thereof. The sleeve forms a band for holding the sections together. Further details of the invention will appear from the following description.

In the form of the invention illustrated, 70 the shield comprises a pair of sections 10 and 11 preferably formed of relatively hard sheet metal, each section having formed at its inner end a flange 12 and at its outer end a flange 13. When the sections are positioned 75 one on the other as shown in Fig. 1, the flanges 13 of the two sections are disposed in the same plane and the flanges 12 at the other end are disposed in a single plane.

After the sections have been positioned as 80 illustrated in Fig. 1, a sleeve 15 of relatively soft or ductile metal is placed around the outer surface of the inner portions of the sections in abutting relation to the flanges 12, 12. The sleeve 15 is preferably tapered in 85 thickness from end to end, the thicker end being disposed at the inner end of the shield.

The shield illustrated is preferably expanded by a driven expanding member, such as a nail 18 having a diameter so proportioned to 90 the bore of the tubular member that the shield sections will be expanded when the expanding member is driven into the shield. As the shield is expanded, the soft metal sleeve 15 is forced outwardly into firm gripping 95 engagement with the wall opening and because of the taper of the shield and the flanges 12, 12 at the inner end thereof, the ductile metal will be forced laterally and will not flow to any material extent longitudinally of 100

the shield. The ductile sleeve, therefore, therebetween a bore tapered from the inner end toward the outer end thereof, and a sleeve of relatively soft metal tapered in thickness from end to end encircling said sections and securing the sections together. 70

5 6. The nail or expanding member 18 has a head 19 at its outer end which serves to reinforce the flange 13, 13 at the outer end of the shield. 75

10 7. Although one specific embodiment of the invention has been particularly shown and described, it will be understood that the invention is capable of modification and that changes in the construction and in the arrangement of the various cooperating parts 15 may be made without departing from the spirit or scope of the invention, as expressed in the following claims. 80

What I claim is:

20 8. 1. An expansion shield comprising a tubular member of relatively hard metal of uniform thickness tapered from the inner end toward the outer end thereof and having a laterally projecting flange at its inner end 25 and a sleeve of relatively soft metal superimposed on the outer surface of the tubular member and abutting said flange. 90

95 9. 2. An expansion shield comprising a tubular member of relatively hard metal of uniform thickness tapered from end to end and having a laterally projecting flange at each end and a sleeve of relatively soft metal superimposed on the outer surface of the tubular member and abutting the flange at 100 the inner end thereof. 100

105 10. 3. An expansion shield comprising a tubular member of relatively hard metal of uniform thickness tapered from the inner end toward the outer end thereof and having a laterally projecting flange at its inner end 40 and a sleeve of relatively soft metal tapered in thickness from end to end and superimposed on the outer surface of the tubular member and abutting the flange. 110

115 11. 4. An expansion shield comprising a pair of laterally expansible sections formed of sheet metal of uniform thickness, said sections being constructed and arranged to form therebetween a bore tapered from the inner end toward the outer end thereof, and a sleeve of relatively soft metal encircling said sections and securing the sections together. 120

125 12. 5. An expansion shield comprising a pair of sections formed of sheet metal of uniform thickness, said sections being constructed and arranged to form therebetween a bore tapered from end to end, said sections having laterally projecting flanges at the inner ends thereof, and a sleeve of relatively soft metal encircling said sections, abutting the flanges, and securing the sections together. 130

13. 6. An expansion shield comprising a pair of laterally expansible sections formed of sheet metal of uniform thickness, said sections being constructed and arranged to form

70 75 80 85 90 95 100 105 110 115 120 125 130

7. An expansion shield comprising a tubular member of relatively hard thin sheet metal of uniform thickness tapered from end to end and having a laterally projecting integral flange at each end and a sleeve of relatively soft metal superimposed on the outer surface of the tubular member and abutting the flange at the inner end thereof combined with an expander having a shank adapted to be driven into said member and a relatively thick head adapted to overlie and reinforce the flange at the outer end of the member. 80

In witness whereof, I have hereunto set my hand this 25th day of August, 1927.

RALPH E. OGDEN.
